UNITED STATES PATENT OFFICE.

MILES F. DEACH, OF OAKLAND, CALIFORNIA.

ADJUSTABLE LAMP FIXTURE.

Application filed May 31, 1927. Serial No. 195,377.

This invention relates to improvements in electric fixtures and in particular to that class of fixtures shown and described in my former Patent No. 1,449,658, issued March 5 27, 1923, and my co-pending application filed July 16, 1924, Serial No. 726,399.

The present construction has several improvements not found in my former patents, viz, a cast supporting arm having a 10 rigidly mounted standard providing a member upon which is revolvably mounted a yoke, the yoke in turn being provided with a retaining member through which the lamp rod is inserted, the said standard being provided 15 with yielding engaging means adapted to prevent the free rotational movement of the yoke relative thereto, and the retaining member being provided with like means adapted to yieldingly hold the lamp rod in 20 adjusted position. The said yoke is additionally provided with adjustable means adapted to cause the yoke clamp members to frictionally embrace the retaining member to provide positive means adapted to hold 25 the lamp rod in any desired position relative to the standard.

An object of my invention is to provide an improved electric fixture adapted for general use and which is neat in appearance, 30 comparatively cheap to manufacture, and one that may be easily adjusted to any desired position relative to its support.

Another object of my invention is to provide a fixture of the type designated that 35 embodies in its construction, means adapting it to be readily adjusted to any desired position relative to its support and means adapted to yieldingly retain it in such adjusted position.

40 Still another object of the invention is to provide an electric fixture in which a novel and cheap method is employed in securing together the various parts constituting the device after their assemblage.

45 Other objects and advantages of my invention will be apparent with reference to the annexed drawing forming a part of this specification and in which

Figure 1 is a side elevation illustrating an 50 embodiment of my invention;

Figure 2 is a plan view illustrating one of the various positions to which the fixture may be adjusted relative to its fixed support;

55 Figure 3 is an enlarged sectional detail of a portion of the supporting arm including the rigidly mounted standard, revolvable

yoke, retaining member and lamp rod, also the yielding retaining means for said yoke and lamp rod, the section being indicated by the line 3—3 of Figure 4;

Figure 4 is a sectional detail taken through the parts shown in Figure 3, the section being indicated by the line 4—4 thereof; and

Figure 5 is an edge view of the cup members constituting the retaining member.

Referring to the drawings, the numeral 10 designates a supporting bracket secured in place upon the wall or other support 11 by the screws 12 and which bracket is provided with a horizontally disposed lug 13, 70 which in turn carries a vertically disposed spindle 14.

The supporting arm 15 consists of a cast member provided at one end with a split member 16 having a socket formed therein 75 and adapted to receive the spindle 14 of the bracket and a clamp member 17 providing means for rigidly clamping the arm 15 in any desired position relative to the spindle 14. The other end of the arm 15 is provided 80 with an opening 18 to receive a standard 19, Figure 3, which standard may be threaded at its lower end and screw-seated in the threaded opening 18. Recesses 21 and 22 are provided in opposite sides of the standard and form elongated housings for yielding members, such as, bowed flat springs 23 and 24 that normally bulge outwardly 85 slightly beyond the cylindrical surface of said standard. The upper end of the standard is provided with a head 25 having an exterior groove 26 to form retaining means 90 hereinafter described.

A yoke 27 is mounted upon the standard 19 and consists of a sleeve 28 having an inside diameter to permit a snug rotatable fit about the standard and is revolvably retained thereon by means of a nub 29, Fig. 4, formed in the wall of the sleeve by a punch indent 30, the said nub being so positioned that it 100 enters the groove 26 formed in the head of the standard and holds the sleeve non-removably in place thereon. The upper end of the yoke terminates in a pair of spaced ears 31 and 32 of resilient character adapted 105 to spring relative to each other and between which is secured a retaining member 33.

The retaining member 33 consists of a pair of cup members 34 and 35 having their edges abutting; and one of the cups is provided with a cross-bar 36 "spot welded" at 110 its edges to the inside walls thereof. The

lamp 37, which is of usual construction, is carried at one end of a tubular member 38 and through which the feed wires 39 are threaded, the said member 38 being adapted 5 for insertion through opposite openings 40 and 41 formed in the cylindrical walls of the member 38, one half of each of these openings being formed on opposite sides of the meeting edges 42 of the member 38 as 10 shown in Figure 5. The openings 40 and 41 are slightly larger in diameter than the outside diameter of the tubular member 38 so that said member 38 may be readily inserted therein and held in frictional contact with 15 the lower edges of said openings by means of a yielding member 43 similar to the members 23 and 24, and when positioned has its free ends contacting in binding engagement with the cross-bar 36 and its intermediate 20 section bowed outwardly and impinging against the upper surface of the tubular member 38.

It will be readily seen that the member 38 may be reciprocatively slid through the 25 openings 40 and 41 to adjust the lamp 37 longitudinally, or it may be rotated relative to the member 33, or swung in a vertical or a horizontal plane, or adjusted angularly to any desired position and will be frictionally held in adjusted position relative to the member 33 by the yielding spring member 43.

The side faces of the cup members 34 and 35 are provided with concentrically-positioned 35 concavo-convex sections 44 and 45 through which perforations 46 and 47 are provided for the reception of a clamp bolt hereinafter described, said sections 44 and 45 presenting annular bearing surfaces 48 and 49 positioned on opposite sides of the member 33 and adapted to fit between the ears 31 and 32 of the yoke 31.

Tension members 50 and 51 are positioned 45 against opposite outside faces of the ears 31 and 32 and are provided with central perforations corresponding with the perforations formed in the ears 31 and 32 and the cup perforations 46 and 47, and a clamp bolt 52 extends through all of these members 50 and is provided with a nut 53 adapted, when properly adjusted, to put tension upon the various parts to cause the ears 31 and 32 to frictionally embrace the bearing surfaces 48 and 49 of the member 33.

55 I claim:

1. In a device of the class described, a standard, a yoke carried by said standard for coaxial rotation with respect thereto, a rod retaining member carried by said yoke, 60 a lamp-supporting rod slidably mounted in said retaining member for longitudinal movement through said yoke, yielding means mounted in said standard and adapted to frictionally engage said yoke to normally retain 65 said yoke in adjusted position, and

yielding means mounted in said retaining member adapted to frictionally engage said lamp rod.

2. In a device of the class described, a standard, a yoke carried by said standard, 70 a rod retaining member carried by said yoke and provided with perforations, a lamp rod mounted in said retaining member and supported in said perforations for longitudinal adjustment therethrough, and yielding 75 means mounted in said standard and in said retaining member and adapted to frictionally hold said yoke and lamp rod in adjusted positions.

3. In a device of the class described, a supporting member adapted to be rigidly mounted, a radially movable arm associated with said supporting member, a standard carried by said arm, a yoke mounted upon said standard and consisting of a sleeve having ears formed at its upper end, a retaining member interposed between said ears and provided with perforations, a lamp rod slidably mounted in said perforations, yielding means mounted in said retaining member 90 and positioned to engage said rod to frictionally retain the same against movement, and yielding means mounted in said standard and positioned to engage said yoke sleeve to frictionally hold it against rotational movement relative to said standard. 95

4. In a device of the class described, a supporting member, a radially movable arm associated therewith, a rigidly mounted standard carried by said arm, a yoke mounted 100 upon said standard and consisting of a sleeve adapted for revoluble movement relative to said standard and having ears formed at its upper end, a retaining member interposed between said ears, means carried by said ears 105 adapted to frictionally embrace said retaining member, perforations formed in opposite sides of said retaining member, a lamp rod mounted in said perforations and slidably adjustable relative to said retaining member, yielding means carried by said standard and adapted to frictionally engage 110 said sleeve, and yielding means carried by said retaining member and adapted to frictionally engage said rod. 115

5. In a device of the class described, a supporting member, a radially movable arm associated therewith, a rigidly mounted standard carried by said arm, a yoke mounted upon said standard and consisting of a sleeve 120 adapted for revoluble movement relative to said standard and having resilient ears formed at its upper end, a retaining member interposed between said ears, means carried by said ears adapted to frictionally embrace 125 said retaining member, perforations formed in opposite sides of said retaining member, a lamp rod mounted in said perforations and slidably adjustable relative to said retaining member, retaining means carried by said 130

sleeve and standard and adapted to prevent their disassemblage, yielding means carried by said standard and adapted to frictionally engage said sleeve, and like yielding means carried by said retaining member and adapted to frictionally engage said rod.

6. In a device of the class described, a support, a retaining member mounted thereon for horizontal and vertical swinging movement, said retaining member consisting of an annular hollow member having a passage therethrough defining a chord of its circle, a lamp rod slidably mounted in said passage, frictional means embracing said retaining member and adapted to prevent its free movement relative to its support, and yielding means carried by said retaining member and adapted to frictionally engage said rod to prevent its free movement relative thereto.
7. In a device of the class described, a support, a retaining member mounted thereon for horizontal and vertical swinging movement relative thereto, said retaining member consisting of a pair of cup members having their edges abutting to form a hollow annular member, a partition strip mounted in said retaining member, and perforations formed in opposite walls thereof, a lamp rod

slidably mounted in said perforations, frictional means embracing said retaining member and adapted to oppose its free swinging movement relative to its support, and yielding means mounted between said partition strip and said rod and adapted to oppose its free sliding movement relative to said retaining member.

8. In a device of the class described, a support, a retaining member mounted thereon for horizontal and vertical swinging movement relative thereto, said retaining member consisting of a pair of cup members having their edges abutting to form a hollow annular member, a partition strip mounted in said retaining member, and perforations formed in opposite walls thereof, a lamp rod slidably mounted in said perforations, said perforations being larger in diameter than said rod, frictional means embracing said retaining member and adapted to oppose its free swinging movement relative to its support, and yielding means interposed between said partition strip and said rod.

In testimony whereof, I affix my signature.

MILES F. DEACH.
